UNITED STATES PATENT OFFICE.

WILLIAM S. STAIR, OF BROOKLYN, NEW YORK, ASSIGNOR TO SHIPLEY CONSTRUCTION AND SUPPLY COMPANY, OF BROOKLYN, NEW YORK, A CORPORATION OF NEW YORK.

REFRIGERATOR-DOOR LOCK.

Application filed March 14, 1922. Serial No. 543,721.

To all whom it may concern:

Be it known that I, WILLIAM S. STAIR, a citizen of the United States of America, residing at Brooklyn, county of Kings, and State of New York, have invented certain new and useful Improvements in Refrigerator-Door Locks, of which the following is a full, clear, and exact description.

The invention which forms the subject of this application for Letters Patent is an improvement in locks designed especially for refrigerator doors and a correct comprehension of its construction and functions will show its applicability, not only to such doors, but for other uses where similar conditions obtain.

In the case of large refrigerator doors it is important that a strong reliable lock be provided that will not jar loose and permit the door to open or lose its insulating value at the joint. It frequently happens, moreover, that the doors after remaining tightly closed or locked for any length of time stick or freeze which makes it difficult to open them, and finally repeated opening and closing with the attendant manipulation of the locking means requires that any device used as a lock shall be strongly constructed and immune to the troubles that inevitably result from undue wear or injury.

To meet all of these practical requirements I have devised a locking device for doors of this character which being distinguished from those heretofore used for the purpose mainly in the form and relation of its component parts may be most readily understood from the drawing and the detailed description of the same which follows:

Fig. 1 is a perspective view of my improved lock.

Fig. 2 is a side view of the same looking from the left, and

Fig. 3 is a partly diagrammatic view of parts of a door, the jamb and the locking mechanism in two indicated positions.

In carrying out my invention I employ two plates 1 and 2, the former adapted for attachment to the jamb, the latter to the door proper. Plate 1 is formed or provided with two upright plates or brackets 3 which afford bearings for a spindle 4. The upper end of this spindle carries a casting properly secured thereto which has a rounded hub 5 surrounding the spindle 4 and side flanges 6 and 7, the former constituting vir-

tually a flat ledge or shoulder. Extending from the hub 5 is a curved arm 8 preferably carrying a roller, and secured to the spindle 4 immediately below the hub 5 is a ratchet wheel 9 with the teeth of which engages a pin 10 set in the end of the hub. A spring 11 surrounds the spindle and has its ends fast to the lower bracket 3 and to the ratchet wheel 9. By this means the spindle may have imparted to it a tendency to turn about its axis, such tendency being adjustable by turning the ratchet wheel 9 in reference to the locking pin 10.

The door plate 2 carries two brackets 12 which afford bearings for a casting or forging composed of a hub formed with a cam part 13 and a curved arm 14. A handle 15 of any proper or desired character extends to the right from the hub or cam 13 and to this handle is connected a rod 16 which extends through the door and is connected with a spring 17. The rod 16 has a head 18 which, under the tension of the spring 17, tends to draw the handle 15 towards the handle side of the door or into its normal position.

As thus designed and assembled the parts described function as follows: When the door 19 is closed the curved arm 14 comes over and in contact with the hub 5 whereupon the inner point 21 of the cam 13 engages the right hand flange 7 of the hub 5 which turns said hub and thereby throws the curved arm 8 towards the door or to the right. The end of arm 8, preferably carrying a roller, travels over the outer edge of cam 13 as is shown in Fig. 3. By this means the door is firmly and effectively locked and will so remain until the handle 15 is operated.

To unlock the door the handle 15 is pulled from the handle side or pushed from the opposite side away from the face of the door with the result that the curved arm 14 is shifted and its end engages with and forces the flange 6 towards and against the plate 1 attached to the door jamb 20. Should the door have stuck or frozen this starts it up and it also turns the curved arm 8 to the left or out of overlapping engagement with the cam 13, which unlocks the door 19 and permits it to be pulled or pushed open.

The form and character of certain of the above-described parts not being of the es-

sence of my invention may be greatly varied. This refers more particularly to the handle used, the kind of spring that acts upon it and other minor details. What, however, I claim as of my invention and now seek protection for is:—

1. A locking means for doors comprising, in combination, a pivoted member on the door provided with a handle and movable about its pivotal support in a plane at right angles to the door, a pivoted member on the door jamb also movable at right angles to the jamb, and formed with a projecting part with which the door member engages, and by which, when said door member is moved, it will be turned about its pivotal support, and a projection on the said jamb member that is forced over and into overlapping engagement with the said door member to thereby form a lock which prevents the outward movement of the door member.

2. A locking means for doors comprising, in combination, a spring actuated pivoted member mounted on the door, provided with a handle and movable in a plane at right angles to the door, and a spring actuated member pivotally mounted on the door jamb, and movable at right angles to the door jamb, and formed with a projecting part with which the door member engages, and by which, when said door member is moved, it will be turned about its pivotal support, and a projection on said jamb member that is forced over and into overlapping engagement with the said door member to thereby form a lock which prevents the outward movement of the door member.

3. A locking means for doors comprising, in combination, a plate having brackets adapted for attachment to the door jamb, a spindle mounted in said brackets and a member having a projecting part and mounted thereon, a plate having brackets adapted for attachment to the door, a spindle mounted in said brackets and a member having a cam portion and an arm mounted on the spindle, said cam being adapted, when the door is closed, to engage and turn the spindle member on the jamb and to thereby swing the projection forming a part thereof into overlapping engagement with itself and thereby form a lock.

4. A locking means for doors comprising, in combination, a plate having brackets adapted for attachment to the door jamb, a spindle mounted in said brackets, a member mounted thereon and having side flanges and a curved arm, a plate having brackets adapted for attachment to the door, a spin-

dle mounted in said brackets, a member mounted thereon having a cam surface and a curved arm, said cam surface being so formed that when the door is closed it engages one of the flanges on and turns the spindle member on the jamb and swings its curved arm into overlapping engagement with itself and thereby forms a lock.

5. A locking means for doors comprising, in combination, a plate adapted for attachment to the door-jamb, a revoluble spring actuated member having side flanges and a curved arm mounted on said plate, a plate adapted for attachment to the door, a casting revolvably mounted thereon and having a cam portion to engage with one of the flanges on the spring actuated jamb member and a curved arm to engage with the other flange, and a handle for turning said casting.

6. A locking means for doors comprising, in combination, a plate adapted for attachment to the door jamb, a revoluble spring actuated member having side flanges, one of which is adapted to be brought into engagement with the jamb when the member is turned, and a curved arm mounted on said member, a plate adapted for attachment to the door, a member revolvably mounted thereon and having a curved arm, adapted to engage with the above mentioned flange on the spring actuated jamb member and a cam portion to engage with the other side flange whereby said spring actuated jamb member is capable of being turned in opposite directions, a handle attached to the revoluble door member and a spring acting to draw the same toward the face of the door.

7. A locking means for doors comprising, in combination, an arm pivoted to the door and having a cam portion, and a movable member on the door jamb having a projecting part thereon, which by the engagement of the said cam with the movable member on the door jamb is forced into locking engagement with the said arm.

8. A locking means for doors comprising, in combination, an arm pivoted to the door and having a cam portion, and a cooperating spring actuated arm with flanged extensions adapted to be forced into locking engagement with the arm which is pivoted to the door when the latter while its cam is in engagement with one of the said flanges is turned.

In testimony whereof I hereto affix my signature.

WILLIAM S. STAIR.
